UNITED STATES PATENT OFFICE

CLEMENT K. STODDER, OF BROOKLINE, MASSACHUSETTS

PROCESS OF PRODUCING SOAP POWDER FROM SOAP STOCK HIGH IN FATTY ACID

Application filed August 28, 1928. Serial No. 302,632.

This invention relates to a cold process of producing soap powder from crude soap stock high in fatty acids, such, for example, as cotton-seed soap stock.

5 Such soap powder is used largely as a base for cleaning compositions.

Crude soap stock which contains a high percentage of fatty acids is a plastic or semi-plastic substance which cannot be committed or ground to produce a soap powder. In usual processes of making soap powder from soap stock containing a high percentage of fatty acids, such as cotton-seed soap stock, the soap stock is first boiled in a kettle with 15 live steam, water, a caustic and salt, thereby producing a liquid mixture or composition which is then run into a mixing tank or crutcher into which sufficient soda ash is introduced, while the mixture or composition is 20 in a hot liquid state, to produce a thick and pasty hot soap. This hot soap is then placed in barrels or other receptacles and upon cooling produces a hard soap. This hard soap is thereafter broken up and ground to produce 25 a soap powder.

Ordinarily in the manufacture of commercial cleaning compositions, other ingredients, including certain chemicals and sometimes abrasives, are mixed with this hard soap, 30 after it is broken up, and ground with the soap to the desired fineness of the cleaning composition.

The present invention relates to the production by a cold process, from a crude soap 35 stock containing a high percentage of fatty acids, such as cotton-seed soap stock, of a soap powder which may be used directly as a soap or which may be mixed with other ingredients, as aforesaid, to produce a cleaning composition.

In accordance with the present invention the semi-plastic crude soap stock, such as cotton-seed soap stock, is divided into pieces of substantially uniform cross-sectional area 45 presenting large surface areas relatively to the mass thereof and said pieces subjected to the action of an alkali in powdered form having an affinity for the moisture of the soap stock, then permitting the alkali to absorb a substantial proportion of the moisture of the

soap stock by aging, so that the soap stock will be reduced to a brittle condition, and thereafter reducing the mixture to a desired degree of fineness. In the practical use of the method the crude soap stock is first broken 55 up into relatively small pieces and such pieces desirably are so treated as to produce strips of substantially uniform cross-sectional area and preferably of cylindrical form.

This can be readily accomplished by subjecting the pieces of cotton-seed soap stock to extrusion through a suitable grid having apertures of the desired size. The strips of cotton-seed soap stock thus obtruded are then 60 mixed directly with soda ash in powdered form, preferably in the approximate proportions of one pound of soda ash to two pounds of cotton-seed soap stock. During the extrusion process the soap stock forms in relatively 65 short strips or ribbons, and the powdered soda ash adheres to and in effect coats the pieces of soap stock while the excess of soda ash surrounds and more or less embeds the 70 pieces of soap stock.

This mixture is permitted to age for a considerable length of time, such, for example, as one or two days, during which the intimate association of the soda ash and the soap stock dries or reduces the cotton-seed 75 soap stock to a brittle condition, in which it can be readily ground. Under certain conditions the moisture contained in the mixture after the drying-out process imparts to the mixture a proper consistency to permit of 80 its being directly ground to form a soap powder. Under other conditions, however, too much moisture is eliminated from the soap stock during the drying-out or aging process, so that additional moisture is required 85 to produce the desired result.

Additional moisture may be supplied by adding to the mixture, if too dry, a granular moisture containing alkali, such as sal soda, in sufficient quantities to restore the moisture 90 content to the mixture, which may then be reduced or ground to the desired degree of fineness.

If desired to produce a cleaning composition, other ingredients, chemicals, and, if de- 100

sired, abrasive material may be added during the grinding or reducing operation to produce the desired cleansing composition, or the soap powder may be subsequently ground 5 with such additional ingredients, chemicals and abrasives to produce the desired cleaning compound.

It will be understood that while the present process has been described with particular 10 reference to cotton-seed soap stock, it is equally applicable to other forms of crude soap stock, such as tallow soap stock, grease soap stock or vegetable oil soap stocks which comprise a high percentage of fatty acids.

15 A preferred form of apparatus for performing the cold process method of producing soap powder from crude soap stock high in fatty acids is illustrated in the accompanying drawings, in which:

20 Figure 1 is a more or less diagrammatic view of associated apparatus for producing the mixture before grinding or reducing; and

25 Figure 2 is an illustration of suitable apparatus for reducing and grading the soap powder.

The crude soap stock after having been broken up into irregular pieces is placed in the hopper 1 of a feeder 2 and is carried by 30 an endless belt 3, which extends beneath the hopper 1 and is driven by a pawl and ratchet mechanism 4 to the hopper 5 of an extruding machine 6. The extruding machine 6 desirably is provided with a feeding screw 7 which 35 forces the soap stock through a grid 8 at the lower end of the extruding machine. The soap stock thus forced through the grid is in the form of ribbons or cylindrical strips, and as it is extruded from pieces of more or less 40 irregularity breaks up into relatively short pieces. The extruded pieces are delivered to a hopper 9 leading to a mixing machine 10.

Soda ash is placed in a hopper 11 which, at 45 its lower end, communicates with the feeding device which, as illustrated, comprises a screw 12 which delivers the material at any desired rate, according to the rate at which the screw is driven, to a chute 13 which leads to the hopper 9, so that soda ash passes into 50 the mixing machine with the extruded pieces of soap stock. Any suitable type of mixing machine may be employed. As illustrated, the mixing machine comprises a cylinder 14 having a shaft 15 extending longitudinally 55 thereof, which is provided with a series of blades 16 adapted to mix the soap stock and soda ash and to carry it forward from the feeding end to the delivery end of the cylinder, from which it is delivered through a 60 spout 17 to a barrel 18 or other receptacle.

The mixture thus accumulated in the barrel is permitted to age for a sufficient length of time to enable the soda ash to reduce the amount of moisture in the soap stock suffi- 65 ciently to cause the soap stock to become brit-

tle. The soap stock may then be ground or otherwise reduced to produce a soap powder.

In Fig. 2 a preferred form of reducing apparatus is shown which comprises a beater or pulverizer 19 having a hopper 20 into which soap stock is emptied from the barrel or other receptacle 18. The beater comprises a preferably cylindrical drum 21 having a central shaft 22 extending longitudinally thereof with a series of beater arms 23 pivotally mounted upon and desirably spirally arranged about the shaft 22. The beaters cooperate with the perforated concave 24 within the drum, and the pulverized material is delivered through the apertures in the concave to the lower portion of the drum, from which it escapes or is forcibly delivered through an outlet 25 and may be packaged in any suitable manner.

If during the aging process too much moisture has been eliminated from the mixture, additional moisture may be supplied by introducing into the hopper 20, manually or otherwise, a sufficient amount of sal soda to restore the mixture to the proper moisture content, or the sal soda may be introduced directly into the mixture before it is placed in the hopper of the reducing machine.

In the construction illustrated in the drawings, which is adapted to produce material of particularly uniform fineness, the soap powder is delivered from the outlet 25 of the reducing machine directly upon a reciprocating screen or bolt 26 of a desired mesh, through which soap powder of the desired fineness passes into a suitable receptacle 27. The soap powder which does not pass through the screen is collected in a suitable receptacle (not shown) and may be returned to the hopper 20 of the grinding machine, to be reground.

Where it is desired to produce a commercial cleansing powder, additional ingredients, including chemicals, such as chemical salts and, if desired, abrasives, may be introduced into the hopper 20 of the reducing machine along with the mixture above described, and in passing through the mixture machine will be reduced and intimately mixed with the soap powder, so that the resulting product will be a powdered chemical composition of the desired character and fineness.

It will be readily understood that various types of apparatus may be employed to perform the process above described, and that the particular apparatus generally described herein is of an illustrative and not restrictive character.

Having thus described the invention, what is claimed as new and desired to be secured by Letters Patent, is:

1. A cold process of producing soap powder from a semi-plastic, moisture-containing soap stock which comprises dividing the plastic soap stock into pieces of large sur-

5 face areas relatively to the mass of said pieces, embedding said pieces in a dehydrated powdered alkali having an affinity for the moisture in said moist soap stock, and aging the mixture to permit the alkali to absorb a substantial proportion of the moisture and thereby render the soap stock brittle and then reducing the mixture to a desired fineness.

10 2. A cold process of producing soap powder from a semi-plastic, moisture-containing soap stock high in fatty acids, which comprises forming by extrusion the plastic soap stock into strips of small cross sectional area, embedding the extruded strips in a dehydrated powdered alkali having an affinity for the moisture of said soap stock, aging the mixture to permit the alkali to absorb a substantial proportion of the moisture and thereby render the soap stock brittle and then reducing the mixture to a desired fineness.

15 3. A cold process of producing soap powder from a semi-plastic, moisture-containing soap stock which comprises dividing the plastic soap stock into pieces of large surface areas relatively to the mass of said pieces, embedding said pieces in a dehydrated powdered alkali having an affinity for the moisture in said moist soap stock, and aging the mixture to permit the alkali to absorb a substantial proportion of the moisture and thereby render the soap stock brittle, adding to the mixture, if too dry, a granular moisture-containing alkali in sufficient quantities to restore the proper moisture content to the mixture and then reducing the mixture to a desired fineness.

20 4. A cold process of producing soap powder from a semi-plastic cotton-seed soap stock which comprises dividing the plastic soap stock into small pieces presenting large surface areas relative to the mass of said pieces, embedding said pieces in soda ash of granular form, aging said mixture to permit the alkali to absorb a substantial proportion of the moisture and thereby render the soap stock brittle, and then reducing the mixture to a desired fineness.

25 5. A cold process of producing soap powder from a semi-plastic cotton-seen soap stock which comprises forming the plastic soap stock into pieces of substantially uniform cross-sectional area, mixing with said pieces soda ash in granular form, aging said mixture until said pieces of soap stock become dry and brittle, adding sal soda to said mixture, if too dry, in sufficient quantities to restore the proper moisture content thereto, and finally reducing the mixture to a desired fineness.

30 6. A cold process of producing soap powder from a semi-plastic cotton-seed soap stock which comprises forming by extrusion the plastic soap stock into strips of small

35 cross sectional area, embedding the extruded strips in soda ash of granular form in approximately the proportion of one pound of soda ash to two pounds of said cotton-seed soap stock, aging the mixture to permit the soda ash to absorb a substantial proportion of the moisture and thereby render the soap stock brittle, and then reducing the mixture to a desired fineness.

40 7. A cold process of producing soap powder from a semi-plastic cotton-seed soap stock which comprises forming the plastic soap stock into strips by extrusion, subjecting the extruded strips to the action of soda ash in the approximate proportion of one pound of soda ash to two pounds of cotton-seed soap stock, aging the mixture until the soap stock becomes dry and brittle, adding sal soda to the mixture, if too dry, in sufficient quantities to restore the proper moisture content to said mixture, and reducing the mixture to a desired fineness.

45 In testimony whereof, I have signed my name to this specification.
